(57) CLAIM

The ornamental design for headwear as shown and described.

DESCRIPTION

1. Headwear

1.1 :Front

1.2: Right

1.3: Top

1.4 : Left

1.5: Back

1.7 : Left

The design is headwear for wearing over the head of a wearer; figure 1.1 is a front view of the headwear with straps open; figure 1.2 is a right view of the headwear with the straps open; figure 1.3 is a top view of the headwear; figure 1.4 is a left view of the headwear with the straps open; figure 1.5 is a rear view of the headwear; figure 1.6 is a right view of the headwear with the straps closed; figure 1.7 is a left view of the headwear with the straps closed.

The broken line outline of the partial human figure in Figures 1.1-1.7 assists in illustrating how the headwear may appear when in a position of use, but forms no part of the claimed design.
